UNITED STATES PATENT OFFICE.

LE ROY CAHILL, KALAMAZOO, MICHIGAN.

SULKY-PLOW CARRIAGE.

SPECIFICATION forming part of Letters Patent No. 229,375, dated June 29, 1880.

Application filed April 2, 1880. (No model.)

To all whom it may concern:

Be it known that I, LE ROY CAHILL, of Kalamazoo, in the State of Michigan, have invented certain new and useful Improvements in Sulky-
5 Plow Carriages; and I do hereby declare that the following is a full, clear, and exact description thereof, reference being had to the accompanying drawings, and to the letters of reference marked thereon, making a part of
10 this specification.

My invention relates to sulky-plow carriages; and it consists in the construction and arrangement of devices for turning the axles to adjust the wheels, as will be hereinafter more
15 fully set forth.

In order to enable others skilled in the art to which my invention appertains to make and use the same, I will now proceed to describe its construction and operation, referring to the
20 annexed drawings, in which—

Figure 1 is a vertical longitudinal section; Fig. 2, a face view thereof, showing one mode of attaching lever; Fig. 3, a side elevation of the device attached to the axle, and Fig. 4 a
25 front or face view.

In a sulky-plow carriage such as I propose more particularly to apply my invention to there is under each end of the axle-tree a forked casting or a double hanger, or one or
30 two downwardly-projecting arms, through which the short axle is passed. A represents this short axle, which is formed with an arm, B, extending at right angles to it, and at the end of this arm projects the spindle C to receive the driving-wheel. In other words, the
35 axle A is formed with a crank in the usual manner.

On the axle A is placed a casting composed of a socket or collar, D, circular disk D', and
40 semi-tube or half-barrel D², all in one piece. The socket or collar D is slipped over the axle A, the part D² fitting around the inside of the arm B, while the disk D' projects in the opposite direction from the axle, as shown.

45 One arm of the hanger comes close up to the socket D, and a collar, F, is placed on the axle against the opposite side of the hanger-arm and fastened by a set-screw, a, whereby the casting is held in place on the crank of
50 the axle. However, if deemed necessary, the half-barrel of the casting may be held or fast-

ened to the crank by any suitable or convenient means.

On the face of the disk D' are made two or more grooves, b, running diametrically, for the adjustment of a lever, G, which is fastened by a bolt, h, and nut i, and by which the axle may be turned so as to bring the crank-arm at any angle desired to raise and lower the wheel. The object of adjusting the lever G
55 on the face of the disk is to accommodate the lever to the position of the rack-bar, in which the lever is to be held in the different positions.

By means of the grooves b in the disk there
60 can, however, be but a limited number of adjustments of the lever, and for this reason in some cases I provide the disk D' on its face with a series of radial corrugations, m, and place upon the bolt h a correspondingly-corrugated washer, I, and in the outer side of this
65 washer is a single diametrical groove or recess to receive the lever G, which is then fastened in place by the nut i. In this case there will then be as many adjustments as there are
70 teeth or corrugations on the parts D' and I.

If desired, the castings D D' D² may be
75 permanently fastened to the axle, and the part D' may be of any desired form, round, oval, square, or other shape.

The device D D' D², herein termed "casting," may be made in any other suitable manner besides casting.

Having thus fully described my invention, what I claim as new, and desire to secure by
80 Letters Patent, is—

1. In a sulky-plow carriage, the device herein described, consisting of the socket or collar D, disk D', and semi-tube D², and provided with means for adjusting the lever thereon.

2. The combination, with a crank-axle, of the device D D' D², having the part D' corrugated, as described, the corrugated washer I, lever G, and bolt and nut, substantially as
85 herein set forth.

In testimony that I claim the foregoing I have hereunto set my hand this 2d day of April, 1880.

LE ROY CAHILL.
